(57) **CLAIM**

The ornamental design for a disposable glove dispenser, as shown and described.

DESCRIPTION

FIG. 1 is a front elevational view of the glove dispenser according to my invention;

FIG. 2 is a back elevational view of the glove dispenser of FIG. 1;

FIG. 3 is a side elevational view of one side of the glove dispenser with the opposite side being identical;

FIG. 4 is a top plan view of the glove dispenser of FIG. 1;

FIG. 5 is a perspective view of the glove dispense of FIG. 1; and,

FIG. 6 is a bottom plan view of the glove dispenser of FIG. 1.

The broken-line disclosure of gloves in the views is for illustrative purposes only and forms no part of the claimed design.
